ATTYS

UNITED STATES PATENT OFFICE.

GEORGE P. NICHOLS, OF KENILWORTH, ILLINOIS.

DESIGN FOR AN AUTOMOBILE-HOOD.

46,689.

Specification for Design. Patented Nov. 24, 1914.

Application filed May 5, 1913. Serial No. 765,692. Term of patent 14 years.

To all whom it may concern:

Be it known that I, GEORGE P. NICHOLS, residing at Kenilworth, in the county of Cook and State of Illinois, have invented a new, original, and ornamental Design for Automobile-Hoods, of which the following is a specification, reference being had to the accompanying drawing, forming part thereof.

The figure is a perspective view of an automobile hood, showing my new design.

I claim:

The ornamental design for an automobile hood as shown.

GEORGE P. NICHOLS.

Witnesses:

ANNE SOLOMON,
C. E. KANE.
